UNITED STATES PATENT OFFICE.

CHARLES H. NUMAN, OF NEW YORK, N. Y.

DESIGN FOR A COMBINATION DESK-PAD AND INKSTAND.

47,495.

Specification for Design.

Patented June 22, 1915.

Application filed April 2, 1915. Serial No. 18,833. Term of patent 3½ years.

To all whom it may concern:

Be it known that I, CHARLES H. NUMAN, a citizen of the United States, residing at New York city, in the county and State of New York, have invented a new, original, and ornamental Design for a Combination Desk-Pad and Inkstand, of which the following is a specification, reference being had to the accompanying drawings, forming a part thereof, and in which—

Figure 1 is a perspective view, Fig. 2 a

top view, and Fig. 3 an edge view of a combination desk pad and inkstand embodying my design.

I claim:

The ornamental design for a combination desk pad and inkstand, substantially as shown.

CHARLES H. NUMAN.
